UNITED STATES PATENT OFFICE.

WILLIAM TWEEDDALE, OF BROOKLYN, ASSIGNOR TO THE J. L. MOTT IRON WORKS, OF NEW YORK, N. Y.

DESIGN FOR A FIRE-PLACE.

SPECIFICATION forming part of Design No. 18,309, dated September 19, 1882.

Application filed August 11, 1882. Term of patent 7 years.

To all whom it may concern:

Be it known that I, WILLIAM TWEEDDALE, of Brooklyn, in the county of Kings and State of New York, have invented a Design for Fire-Places and Grates, of which the following is a specification.

This design, which includes the fire-place frame, grate, and fender, is composed chiefly of round ornaments, checkered or cross-bar ornaments, and leaflet ornaments, forming as a whole an artistic appearance somewhat resembling Egyptian architecture.

The fender has a base, *a*, with beveled upper surface, a row of circular and leaflet ornaments, *b*, a central ornament, *c*, with curved edges and ornamental surface, as shown. The corner-pieces *d* of the fender are checkered cross-bars, with central and corner ornaments, as shown. The scroll *e* and bar *f* and castellated work *g* form the edge of the fender, and there are leaflet-scrolls *h* at each side of the central ornament, *c*. A round rail, *i*, with conical ornaments and collars, forms the top of the fender, and there is a central piece, *m*, with diamond surface ornaments, as shown.

The fire-place frame has corner ornaments, *d'*, generally similar to the ornaments *d*; also, a bar, *n*, across the top, with conical and collar ornaments. The checker ornaments at *o* are on the surface of the frame. The fire-place

frame has projecting bases at *p*, above which rise the round ornaments *q*, with the bands and the elliptical and conical shapes shown, and there are stems with round ornaments at *r*. The surface of the frame is paneled with 35 leaflet surface ornaments, as shown.

The grate-frame has the ornamental front bars, *s*, side posts and top ornaments, *t*, as represented, and a back with a row of ornaments, *u*, a central square frame, *w*, inclined to side pediment at *v*, and angle ornaments *x*, as shown.

I claim as my invention—

1. The design of the fender, composed of the checker ornaments *d*, circles, scrolls, and leaflets, and the round bars with collars and ornaments, substantially as shown. 45

2. The design of the fire-place frame, composed of the checker ornaments *d'*, bars, round ornaments with collars, and the stems, panels, 50 and leaflet ornaments, substantially as shown.

3. The design of the grate-frame, composed of the front bars, side posts, and back, ornamented substantially as shown.

Signed by me this 7th day of August, A. D. 55 1882.

WILLIAM TWEEDDALE.
